L. H. PALMER.
STARTING DEVICE FOR ELEVATORS.
APPLICATION FILED MAY 14, 1921.

1,414,040.

Patented Apr. 25, 1922.

UNITED STATES PATENT OFFICE.

LOUIS H. PALMER, OF HURDSFIELD, NORTH DAKOTA.

STARTING DEVICE FOR ELEVATORS.

1,414,040.

Specification of Letters Patent. Patented Apr. 25, 1922.

Application filed May 14, 1921. Serial No. 469,625.

To all whom it may concern:

Be it known that I, LOUIS H. PALMER, a citizen of the United States, residing at Hurdsfield, in the county of Wells and State 5 of North Dakota, have invented certain new and useful Improvements in Starting Devices for Elevators; and I do hereby declare the following to be a full, clear, and exact description of the invention, such as 10 will enable others skilled in the art to which it appertains to make and use the same.

This invention relates to a starter or an auxiliary propelling means for an elevator and is shown particularly as applied to a 15 cup belt elevator used in grain elevators. The elevators, particularly the cup belt grain elevators, often become choked and the motion thereof stopped. When such choking occurs it has been necessary for the operator 20 to go into the basement or pit at the bottom of the elevator and dig out the grain, which grain must be carried up out of the pan from which the elevator normally takes it. The 25 pan or pit is usually small and dusty and a disagreeable place to work.

It is an object of the invention, therefore, to provide means by which such a choked elevator may be started from a position at the side of the leg or housing of the 30 elevator.

It is a further object of the invention to provide such means which is constructed to be fastened to legs of various sizes and which can be readily removed from one leg 35 to the other.

It is still another object of the invention to provide such a device for starting the elevating means that when said means is started it will offer no obstruction to the continued 40 operation of the elevator.

These and other objects and advantages of the invention will fully appear from the following description made in connection with the accompanying drawings in which—

45 Fig. 1 is a view in front elevation of the device as applied to an elevator leg;

Fig. 2 is a central vertical section of the device; and

Fig. 3 is a perspective view of a portion 50 of the device.

Referring to the drawings, an elevating means comprising a belt 1 and attached buckets 2, is shown, which elevator is enclosed in the housing or leg 3. The side 55 of the leg illustrated in Figs. 1 and 3 is that between the upwardly moving and

downwardly moving sides of the elevator, the belt 1 moving upwardly, as indicated by the arrows in Fig. 2. The side of the leg or housing is cut away at the points 3^a to provide an opening which is designed, either to receive a cover or the device of the present invention. The latter comprises upper and lower transversely extending members 4 which are provided at each end with centrally disposed longitudinally extending slots 4^a. The members 4 are suitably spaced to be received in the opening in the housing wall and are centrally connected by a bar 5 extending therebetween. The member 6 extends transversely across the housing between the members 4 and is provided with a central member 6^a having a channel therethrough through which extends the member 5. On its inner side the member 6 has pivoted thereto, arms 7, and said member has projecting ledges 6^a extending under the members 7 on which the members 7 rest and on which they are held in substantially horizontal position. As indicated in dotted lines 75 in Fig. 3, the inner ends of the member 7 can swing upwardly. The device is secured to the housing by lag screws 8 which extend through the slots 4^a and into the sides of the housing. It may be stated that when the 80 device is not in use the same lag screws are used to fasten the cover to the housing. From the upper side of the members 6 extend spaced members 6^b which are connected by a cross piece 6^c which is also provided with a channel through which the member 5 extends. A pulley or block and tackle device indicated as 10 is secured to the side of the housing above the upper member 4 and a rope or cable member 11 is 85 secured to fastening members projecting from the member 6^c and extends over the device 10 and then downwardly to a convenient position in reach of the operator. 90

When the device is disposed in position on 100 the housing the belt 1 of the elevator extends between the inner end of the member 7 and the member 6, which latter member is provided with a channel to receive the same.

If the elevator becomes choked and 105 stopped, the device will be placed in position on the housing, as shown and described and the cable 11 arranged in position as shown. Power is then applied to the outer end of the cable 11 which is pulled downwardly and the members 6 and 6^a will be pulled upwardly on the member 5. The 110

member 7 will engage under the lower edge of the buckets 2 and an upward pull will thus be exerted on the belt 1. This operation will be continued until the elevator is again started. It will be noted that the buckets can pass the arms 7, so that the members 6 can be lowered past the buckets after having pulled the same upwardly by the arms 7 swinging upwardly, as shown in Fig. 3. After the elevator has been started running in normal operation, the device can be removed and the cover placed on the housing. It will be noticed that by provision of the slots 4^a and the lengths of the members 4, that the device can be applied to housing legs of various sizes.

From the above description it is seen that applicant has provided a simple and efficient means for re-starting a choked elevator. The device is simple and can be readily constructed and transferred to the desired place. It will, of course, be understood that various changes may be made in the form, details and arrangement of the device without departing from the scope of applicant's invention which, generally stated, consists in the matter shown and described and set forth in the appended claims.

What is claimed is:

1. In an elevating device comprising an endless traveling member having spaced members attached thereto, an auxiliary propelling device having means adapted to engage said projecting members, means to move said means in the direction of travel of said endless member, and means holding said first mentioned means in contact with said projecting members, said first mentioned means being arranged to permit the passage of said projecting members in a direction opposite to the normal travel of the endless member.

2. In a lifting device comprising an endless traveling member having spaced members projecting therefrom, an auxiliary propelling device having means adapted to engage under said projecting members, means for moving said first mentioned means upwardly in the direction of travel of said endless member, stops holding said first mentioned means in contact with said projecting members while moving upwardly, said means being constructed and arranged to permit the passage of said projecting members when moving downwardly relative thereto.

3. The structure set forth in claim 1, said first mentioned means comprising a pivoted member adapted to engage with one of said projecting members.

4. A device of the class described comprising spaced members adapted to be secured to the side of an elevator leg, means connecting said members, and a device slidable on said last mentioned means, said device being arranged to receive the traveling belt of an elevator and having a pivoted member secured thereto adapted to engage under the buckets on said belt, and a stop member arranged to hold said pivoted member in engagement with said buckets, said pivoted member being adapted to swing upwardly to permit the passage of the bucket thereby.

5. A device of the class described comprising spaced members adapted to be secured to the side of an elevator leg, a member connecting said members and a movable member slidable on said last mentioned member and adapted to receive the traveling belt of said elevator, members pivoted to each side of said movable means and projecting on the inside of said belt and adapted to engage under a bucket secured thereto, and stop means for holding said pivoted member in engagement with said bucket.

6. The structure set forth in claim 4, a pulley secured to the elevator housing above said members, and a cable attached to said movable member and passing over said pulley, whereby said movable member can be elevated by pulling force applied to said cable.

7. In an elevating device comprising an endless traveling belt and spaced elevated members secured thereto, an auxiliary propelling device adapted to be attached to the housing of the upwardly moving side of the elevator, said device comprising spaced members having slots formed therein to receive attaching means, means connecting said members, and a device slidable on said means and adapted to be moved upwardly thereon, comprising means adapted to engage under the elevating members on said belt and move the same upwardly.

In testimony whereof I affix my signature in presence of two witnesses.

LOUIS H. PALMER.
